ENGINE

Andre J. Meyer, Detroit, Mich., assignor to Continental Motors Corporation, Detroit, Mich., a corporation of Virginia

Application May 11, 1931. Serial No. 536,469

15 Claims. (Cl. 123—81)

My invention relates to internal combustion engines and has particular utility in reference to such engines of the general class known as sleeve valve engines as distinguished from poppet valve engines.

Engines of the class referred to are usually provided with a sleeve pocket generally formed between the cylinder and a re-entrant portion of the cylinder head, one or more sleeves operating within said pocket. Difficulties have been experienced in properly maintaining the sleeve pocket free from deposits or sludge which appear in the form of carbon, rust, and other accumulations.

It is an object of my invention to provide improved and simplified means for maintaining the sleeve pocket free from accumulations.

A further object of my invention resides in the provision of a series of conduits or passages between the usual fuel mixture conducting system for the engine cylinder and the sleeve pocket preferably self contained within the engine structure whereby the sleeve valve means will exert a pumping action on the fuel mixture to circulate the same to keep the sleeve pocket washed and free of deposits. Thus the fuel mixture is circulated between the sleeve pocket and the fuel mixture conducting system carrying from the sleeve pocket any foreign particles, the latter passing to the engine combustion chamber where they are relatively harmless to the engine.

A further important feature of my invention resides in the provision of a novel construction wherein the sleeve valve or valve of the various cylinders of the engine have their upper portions adapted to overtravel the upper face of the cylinder block bounding the cylinders whereby removal of the deposits is facilitated, the deposits being pushed or scraped away from the sleeve pocket.

Other objects and advantages of my invention will be apparent as this specification progresses, reference being made, for illustrating the salient features of one embodiment thereof, to the accompanying drawing in which:

Figure 1 is a sectional elevation view through one of the engine cylinders,

Figure 2 is a plan sectional view along the line 2—2 of Figure 1, and

Figure 3 is a detail sectional view along the line 3—3 of Figure 1.

In the drawing I have illustrated my invention in connection with engine A of the Burt-McCollum type wherein a single sleeve 10 associated with cylinder 11 contained in cylinder block structure 12 is given the customary combined recipro-

cating and oscillating movement for accomplishing the well known cyclical events of the engine. The particular type of sleeve movement as well as the number of sleeves employed per cylinder and other general details form no part of my invention in themselves, my invention being readily adaptable to various types of engines as will be presently more apparent.

Within sleeve 10 is the usual piston 13, sleeve 10 having usual intake and exhaust ports 14, 15 respectively porting with cylinder ports 16, 17 port 16 being supplied with fuel mixture from the usual carburetor (not shown) by way of any suitable fuel mixture conducting means such as intake manifold 18 and cylinder block intake passage 19.

The cylinder block structure 12 has an upper face 20 seating a water jacket cover 21 and the face 24 of a flange 22 of the cylinder head structure 23. A depending portion 24' of the cylinder head is spaced from and within cylinder 11 to provide the sleeve pocket 25 the latter being sealed from combustion chamber 26 by rings 27.

The flange 22 is provided with a conduit or passage 28 in one portion of its under face, this passage extending at one end into the annular recess 29 above the faces 20, 24 adapted to periodically receive the upper portions of the sleeve 10, the recess 29 also being preferably relieved at 30 inwardly of the sleeve.

The cylinder block 12 has a passage 31 opening upwardly at 32 in face 20 and into passage 28 and opening downwardly at 33 into passage 19.

The upper end 34 of sleeve 10 is preferably bevelled downwardly and inwardly to facilitate scraping deposits from the walls of the cylinder 11.

In operation the movement of sleeve 10 in pocket 25 produces a pumping action on the fuel mixture through passages 19, 31, 28 and recess 29, whereby deposits will be continuously removed from the pocket 25 and thence to the passage 19 and combustion chamber 26 as hereinbefore stated. The bevelled edge 34 forms a scraping edge for the cylinder walls facilitating removal of deposits therefrom and the overtravel of the sleeve will force or push the deposits free of the cylinder walls for passage through passage 28.

What I claim as my invention is:

1. In an engine of the sleeve valve type, a cylinder block structure having a cylinder contained therein, a cylinder head structure, a sleeve valve operable between the cylinder and cylinder head structure, said sleeve valve having an upper bevelled scraping edge, said cylinder block struc-

ture provided with a passage adapted to receive deposits from said scraping edge.

2. In an engine of the sleeve valve type, a cylinder block structure having a cylinder contained therein, a cylinder head structure, a sleeve valve operable between the cylinder and cylinder head structure, said sleeve valve having an upper bevelled scraping edge, one of said structures provided with a passage extending laterally of 10 said sleeve valve and adapted to receive deposits from said scraping edge, said sleeve valve overtravelling the upper portion of the cylinder block bounding said cylinder.

3. In an engine of the sleeve valve type, a cylinder block having a cylinder contained therein and provided with an intake port, a fuel mixture conducting means communicating with said intake port, a cylinder head structure closing one end of the cylinder and having a portion 20 thereof depending within the cylinder and spaced therefrom to provide a sleeve pocket, sleeve valve means operable within the cylinder and extending into the sleeve pocket, said sleeve valve means overtravelling the upper portion of the cylinder 25 block bounding the cylinder, said cylinder block having a passage in communication with the sleeve pocket and fuel mixture conducting means.

4. In an engine of the sleeve valve type, a cylinder block structure having a cylinder contained therein and provided with an intake port, fuel mixture conducting means communicating with said intake port, a cylinder head structure closing one end of the cylinder and having a portion thereof depending within the cylinder and spaced 35 therefrom to provide a sleeve pocket, sleeve valve means operable within the cylinder and extending into the sleeve pocket, said sleeve valve means overtravelling the upper portion of the cylinder block bounding the cylinder, said cylinder head structure provided with a flange seated on the cylinder block and recessed annularly to receive the overtravelling portions of the sleeve valve means, one of said structures having a passage 40 extending laterally from said annular recess and in communication therewith.

5. In an engine of the sleeve valve type, a cylinder block having a cylinder contained therein and provided with an intake port, fuel mixture conducting means communicating with said intake port, a cylinder head structure closing one end of the cylinder and having a portion thereof depending within the cylinder and spaced therefrom to provide a sleeve pocket, sleeve valve means operable within the cylinder and extending 50 into the sleeve pocket, said sleeve valve means overtravelling the upper portion of the cylinder block bounding the cylinder, said cylinder head structure provided with a flange seated on the cylinder block and recessed to receive the overtravelling portions of the sleeve valve means, said flange recess communicating with the fuel mixture conducting means.

6. In an engine of the sleeve valve type, a cylinder block having a cylinder contained therein and provided with an intake port, fuel mixture conducting means communicating with said intake port, a cylinder head structure closing one end of the cylinder and having a portion thereof depending within the cylinder and spaced therefrom to provide a sleeve pocket, sleeve valve means operable within the cylinder and extending 70 into the sleeve pocket, said sleeve valve means overtravelling the upper portion of the cylinder block bounding the cylinder, said cylinder head structure provided with a flange seated on the

cylinder block and recessed to receive the overtravelling portions of the sleeve valve means, said cylinder block provided with a passage intermediate the flange recess and the fuel mixture conducting means.

7. In an engine of the sleeve valve type, a cylinder block structure having a cylinder contained therein, a cylinder head structure closing one end of the cylinder, sleeve valve means operably associated with the cylinder, said structures cooperating to provide a pocket for receiving the sleeve valve means, said cylinder block structure provided with a passage opening at one end thereof in the upper face of the cylinder block structure, said cylinder head structure provided with a flange overlying said passage opening and being further provided with a conduit intermediate the passage opening and the sleeve pocket.

8. In an engine of the sleeve valve type, a cylinder block structure having a cylinder contained therein, a cylinder head structure closing one end of the cylinder, sleeve valve means operably associated with the cylinder, said structure cooperating to provide a pocket for receiving the sleeve valve means, said cylinder block structure provided with a passage opening at one end thereof in the upper face of the cylinder block structure, said cylinder head structure provided with a flange overlying said passage opening and being further provided with a conduit intermediate the passage opening and the sleeve pocket, and fuel mixture conducting means for the cylinder, said passage opening at the other end thereof into said fuel mixture conducting means.

9. In an engine of the sleeve valve type, a cylinder block structure having a cylinder contained therein, a cylinder head structure closing one end of the cylinder, sleeve valve means operably associated with the cylinder, said structures cooperating to provide a pocket for receiving the sleeve valve means, one of said structures having a deposit conducting passage, said cylinder head structure provided with a conduit intermediate the sleeve pocket and said passage, said sleeve valve means adapted to project into said cylinder head conduit.

10. In an engine of the sleeve valve type, a cylinder block structure having a cylinder contained therein, a cylinder head structure closing one end of the cylinder, sleeve valve means operably associated with the cylinder, said structures having cooperating faces adapted to seat the cylinder head structure on the cylinder block structure, said sleeve valve means adapted to travel outwardly of the cylinder beyond said faces, one of said faces being recessed for cooperation with the upper portions of the sleeve valve means, said cylinder block structure having a conduit therein communicating with said recess.

11. In an engine of the sleeve valve type, a cylinder block structure having a cylinder contained therein, a cylinder head structure closing one end of the cylinder, sleeve valve means operably associated with the cylinder, said structures cooperating to provide a pocket for receiving the sleeve valve means, fuel mixture conducting means for the cylinder, passage means intermediate the fuel mixture conducting means and the sleeve pocket above the sleeve valve means whereby fuel mixture will be circulated between the fuel mixture conducting means and the sleeve pocket to carry deposits from the sleeve pocket.

12. In an engine of the sleeve valve type, a cylinder block structure having a cylinder con-

tained therein, a cylinder head structure closing one end of the cylinder, sleeve valve means operably associated with the cylinder, said structure cooperating to provide a pocket for receiving the 5 sleeve valve means, fuel mixture conducting means for the cylinder, passage means intermediate the fuel mixture conducting means and the sleeve pocket above the sleeve valve means whereby fuel mixture will be circulated between the fuel mixture conducting means and the sleeve pocket to carry deposits from the sleeve pocket, the movement of the sleeve valve means being adapted to cause said circulation.

13. In an engine of the sleeve valve type, a cylinder block having a cylinder, fuel mixture conducting means for the cylinder, a sleeve pocket structure, sleeve valve means operable within said pocket, passage means intermediate the fuel mixture conducting means and the pocket above the 15 sleeve valve means whereby fuel mixture will be circulated between the fuel mixture conducting means and the sleeve pocket.

14. In an engine of the sleeve valve type, a cylinder block having a cylinder, fuel mixture conducting means for the cylinder, a sleeve pocket structure, sleeve valve means operable within said pocket, passage means intermediate the fuel mixture conducting means and the pocket above the sleeve valve means whereby fuel mixture will be circulated between the fuel mixture conducting means and the sleeve pocket, the movement of the sleeve valve means adapted to cause said circulation.

15. In an engine of the sleeve valve type, a cylinder block structure having a cylinder contained therein, a cylinder head structure, a sleeve valve operable between the cylinder and cylinder head structure, said sleeve valve having an upper bevelled scraping edge, one of said structures provided with a passage adapted to receive deposits from said scraping edge and to conduct the deposits away from the region of said scraping edge.
